(57) CLAIM

The ornamental design for a snap clip for a sling, as shown and described.

DESCRIPTION

FIG. 1 is a bottom, right, front perspective view of a snap clip for a sling showing our new design;

FIG. 2 is a top plan view of the snap clip of FIG. 1;

FIG. 3 is a bottom plan view of the snap clip of FIG. 1;

FIG. 4 is a front elevation view of the snap clip of FIG. 1;

FIG. 5 is a rear elevation view of the snap clip of FIG. 1;

FIG. 6 is a left side elevation view of the snap clip of FIG. 1; and,

FIG. 7 is a right side elevation view of the snap clip of FIG. 1.

The broken lines showing portions of the design in all figures is included for the purpose of illustrating environment and forms not part of the claimed design.
